UNITED STATES PATENT OFFICE.

FRANK WEBER, OF LOUISVILLE, KENTUCKY.

DUMP-WAGON.

1,159,140.

Specification of Letters Patent.

Patented Nov. 2, 1915.

Application filed March 1, 1915. Serial No. 11,284.

To all whom it may concern:

Be it known that I, FRANK WEBER, a citizen of the United States, residing in the city of Louisville, county of Jefferson, and State of Kentucky, have invented a certain new and useful Improvement in Dump-Wagons, of which the following is a specification.

This invention relates to dump wagons, of the class known as "drop bottom dump wagons." It has not heretofore been found practicable to provide wagons of the character described with springs, owing to the restricted space available at the rear of the cart, due to the necessity of allowing space for the downward swing of the valves of the cart, which extend the full length of the cart.

An object of the invention is to provide a wagon of the character described having a spring supported body.

Another object is the provision of economical means of applying springs to wagons of the class described which will be durable and efficient in service.

With the foregoing and other objects in view the invention consists of the novel construction and arrangement of parts illustrated in the accompanying drawing, wherein is set forth an embodiment of the invention, but it is to be understood that such changes and modifications may be resorted to as come within scope of the appended claims.

Referring to the drawing, wherein similar reference characters designate like parts in the several views: Figure 1, is a rear elevation of a wagon to which is applied an embodiment of my invention, parts being broken away to clearly show the construction; Fig. 2, a side elevation of the same with the near wheel removed; Fig. 3, a detail plan of the connections at the ends of the springs; Fig. 4, a rear view similar to Fig. 3, showing a modification; Fig. 5, a side elevation of a portion of the axle showing the retaining loop in position; Fig. 6, a perspective of the spring supporting bolt; Fig. 7, a perspective of the tie plate brace member; Fig. 8, a perspective of the stay rod; Fig. 9, a view of the support used in connection with a single spring; Fig. 10, a modified form of spring supporting bolt.

Referring more particularly to the drawing the reference character —1— designates the body of the wagon, the sides —2— of

which extend rearwardly a spaced distance therefrom. Bolsters —3 and 4— positioned in the rear of the body are secured, by appropriate means, such as straps —5— and bolts —6— to the extended portions of the 60 sides. Springs —7 and 8— preferably semi-elliptic in style, are secured by appropriate means, such as clips —9— to the bolsters 3 and 4. The springs are positioned respectively on each side of and parallel with an axle —10— and are supported thereon by means of bolts —11— which extend through eyes formed on the extremities of the springs. These bolts rest on the axle, and are held thereon against displacement, 70 longitudinally thereof by means of loops —13— which over-lie them and are secured on the axle by suitable means, such as clips —14—. Brace plates —15— each of which comprise a base, or body portion —16— 75 and upturned ends —17— lie against the underside of the axle and are held in position there, by suitable means such as the lower ends of the clips 14, which extend through perforations —18—, in the body. The upturned ends of the plates lie against the outer edges of the springs and are provided with openings —19— which register with loops on the axle and with the eyes 80 in the springs and through which bolts 11 pass. These plates serve to hold the springs in rigid relationship to the axle, preventing any rocking thereon. The heads of the bolts 11 have lateral projections —21— to which stay rods —22— are pivotally secured by suitable means, such as bolts —23—; the stay rods extend rearwardly and are pivotally connected at —24— with brace irons —25— which extend rearwardly and downwardly from the sides of the wagon terminating at a point in the rear of and above the horizontal plane of the axle. In Fig. 4, is illustrated a modification wherein a single spring is mounted directly over the axle, the end of the spring —30— being supported in a chair —31— (see Fig. 9) by means of the bolt 11, passed through perforations —32— in the upturned sides —33— of the chair. The chair is secured on the axle by means of clips 14. In Fig. 10, is shown a modified form of the spring supporting bolt wherein the angular portion —35— is the same size as the body of the bolt, and has a flattened portion —36— which is inserted in a bifurcation —37— in the forward end of 100 105 110 115

the stay rod 22. The stay rod has a similar bifurcation —38— in the rear end thereof to receive the brace iron 25.

Those skilled in the art will readily perceive that with my improved construction the wagon body is free to move up and down, tilt both laterally and longitudinally, and yet is securely held against endwise movement with respect to the axle, *i. e.* is prevented from pitching either backward or forward. From this it follows that, without in any way interfering with the efficiency of the springs, the stay rods 22 act as thrust members to transmit the forward movement of the wagon to the rear axle thereby preventing the body pulling on the springs. By reason of the body braces extending downward and rearward it will be observed that the strain thereon is longitudinal hence there is no liability of their being broken in service.

Having thus described my invention so that anyone skilled in the art pertaining thereto may make and use the same, I claim:

1. In a dump wagon, the combination of a rear axle, a body, springs connected to said body in transverse relationship thereto, bolts positioned on said axle transversely thereof supporting said springs, brace-plates secured to the lower side of said axle and extended upward to embrace said bolts exterior of said springs, a brace extended downward and rearward from said body and terminating to the rear of and in a plane above the level of said axle, and stay-rods pivotally connected with said bolts and said body-braces.

2. In a dump wagon, the combination of a rear axle, a body, springs connected to said body in transverse relationship thereto, bolts positioned on said axle transversely thereof supporting said springs, brace-plates secured to the lower side of said axle and extended upward to embrace said bolts exterior of said springs, a brace extended downward and rearward from said body terminating in a plane above the level of said axle, lateral projections from said bolts and stay-rods pivotally connected with said projections and said body braces.

3. In a dump wagon, a rear axle, a body, springs having eyes in the ends thereof, bolts passing through said eyes, said bolts resting on said axle, loops over-lying said bolts, clips securing said loops on said axle, braces

depending from said body, stay-rods pivotally connected with said bolts and said body braces.

4. In a dump wagon, a rear axle, a body, springs having eyes in the ends thereof, bolts passing through said eyes, said bolts resting on said axle, loops over-lying said bolts, clips securing said loops on the axles, brace-plates secured on the under side of said axle having upturned ends provided with perforations which register with said loops and through which said bolts extend, braces depending from said body, and stay-rods pivotally connected with said bolts and body braces.

5. In combination with an axle, a loop positioned on the upper side thereof, a brace plate positioned against the under side thereof, clips holding said loop and plate in rigid connection with said axle, said plate having upturned ends provided with perforations which register with said loop, springs having eyes in the ends thereof, the ends of said springs positioned between the said upturned ends and the loop, and a bolt passed through said eyes, loop and perforations.

6. In a dump wagon, the combination of a rear axle, a body, springs disposed in parallel relationship to said axle, a bolt arranged transversely of said axle and supporting said springs, a brace-plate secured to the lower side of said axle and extended upward to embrace said bolt exterior of said springs, a brace extended downward and rearward from said body terminating in a plane above the level of said axle and a stay-rod connecting said bolt and body brace.

7. In combination with an axle, a loop positioned on the upper side thereof, a brace plate positioned against the under side thereof, clips holding said loop and plate in rigid connection with said axle, said plate having upturned ends provided with perforations which register with said loop, springs having eyes in the ends thereof, the ends of said springs positioned between the said upturned ends and the loop, a bolt passed through said eyes, loop and perforations, a lateral extension on said bolt and a stay rod pivotally connected with said extension and to the body.

FRANK WEBER.
